UNITED STATES PATENT OFFICE.

COURTLAND F. CARRIER, JR., OF ELMIRA, NEW YORK.

METHOD OF PRODUCING AMALGAMS OR ALLOYS.

No. 895,159.

Specification of Letters Patent.

Patented Aug. 4, 1908.

Application filed January 11, 1907. Serial No. 351,881.

To all whom it may concern:

Be it known that I, COURTLAND F. CARRIER, Jr., a citizen of the United States, residing at Elmira, in the county of Chemung and State of New York, have invented certain new and useful Improvements in Methods of Producing Amalgams or Alloys, of which the following is a specification.

This invention is a method of producing amalgams or alloys by the decomposition of electrolytes in presence of a fluid metal cathode, the object of the invention being to secure a higher efficiency of operation than has heretofore been possible, and to attain other advantages as hereinafter set forth.

The invention will be described by reference to the preparation of alkali metal amalgams by electrolysis of chlorid solutions with a mercury cathode; it is not however restricted to such use, but is applicable to the electrolysis of other aqueous solutions, as well as to the decomposition of molten electrolytes in presence of a fluid cathode of lead or other metal.

In the commercial methods of preparing amalgams of the alkali metals for the production of hydroxid solutions it is usual to electrolyze an alkali chlorid solution in presence of an insoluble anode and a cathode of mercury, the latter in the form of a thin layer beneath the anode; as the mercury becomes charged with sodium it is intermittently or continuously conveyed into the presence of water to oxidize the alkali metal. As this method has been heretofore carried out in practice it possesses several disadvantages, as follows:

(a) The amalgam becomes constantly richer in sodium as it flows from the inlet to the outlet. With the increase in the percentage of sodium in the amalgam, the electrode potential also increases. The result is that the fall of potential is greater near the outlet for the amalgam than near the inlet, thus more of the current flows through the electrolyte at the point farthest from where the amalgam, floating on the surface of the mercury, is to be removed from the action of the electrolyte. It will therefore be seen that more than half of the deposited sodium has to traverse the greater portion of the distance from the inlet to the outlet. This has been partially overcome by the use of a series of long narrow anode and cathode compartments in which the mercury flows across the shorter dimension, but the multiplication in

the number of compartments necessary greatly complicates the apparatus. Under similar conditions, the longer the amalgam is in contact with the electrolyte, the greater will be the loss of sodium by re-solution.

(b) In many of the cells heretofore proposed for the preparation of alkali metal amalgam, the amalgam has to flow out beneath a solid partition which has to extend to a sufficient depth below the surface of the mercury to form a seal between the compartments. The disadvantage of removing from the bottom a material which collects on the surface is self evident.

(c) Perhaps the greatest difficulty rests in the tendency of the mercury to thicken, even with a small percentage of sodium. The sodium collects at or near the surface of the mercury forming a solid amalgam which floats on the main body of the mercury. This crust is retarded at every point where it touches a solid body, so that the velocity of flow tends to be greater near the center than near the sides. The result is that a rich amalgam will be formed near the sides, which will not be carried away as rapidly as the poorer amalgam nearer the center where the mercury current is stronger. The richer the amalgam is the slower it tends to flow. The loss of sodium by re-solution in the electrolyte increases with the duration of the exposure and in this case the richest amalgam tends to remain the longest in contact with the electrolyte. The crust also thickens to some extent at points which are not adjacent to the sides and such portions do not flow as rapidly as the poorer portions of the amalgam, except when the mercury current is very strong. The variation in the rate of flow at the various points on the surface of the mercury tends to distort the "patches" of amalgam crust floating on the surface of the mercury, breaking them up into smaller patches. At every crack or break in these patches, local electrolytic action is set up, which means loss of sodium. By noting the point at which visible evolution of gas takes place, it may be observed that the local action takes place at the edges of the patches and not on the flat upper surface. It is desirable therefore to eliminate as far as possible any agency which tends to cause the breaking up of the patches, and to reduce the time during which those agencies are most active.

(d) From the above, it may be inferred

that any motion of the mercury is a disadvantage, and it has been found by experiment that the rate of re-solution of the sodium increases very rapidly with the agitation of the mercury. It is necessary in practice to have some circulation of the mercury but the ill effect of the agitation involved is reduced by shortening the period of agitation, or by reducing the agitation itself.

(e) A further disadvantage in the commercial cells lies in the fact that the mercury cathode surface is usually greater than the active anode surface. It has been established that the ampere efficiency at the cathode, within practicable limits, rises with the increase of the current density. The maximum current density is limited, not by the capacity of the mercury cathode but by the capacity of the graphite anode. If too high a current density is used at the anode, the graphite will be rapidly eaten away and the increased capacity will be obtained only at a sacrifice of the costly anodes. By having the anode surface larger than the cathode surface, it is possible to obtain the desired high current density at the cathode without running the density at the anode above the critical point. In this way efficiency is gained at the cathode without undue attack on the anodes.

(f) In most commercial cells anode and cathode surfaces are not strictly parallel, but there exists such differences in the current path between the electrodes as result in appreciable differences in the richness of the amalgam at different portions of the surface of the cathode. This results in local action similar to that occurring in the case of the patches above referred to, and reduces the efficiency of the cell.

The disadvantages above noted are avoided or minimized by conducting the electrolysis under conditions as hereinafter set forth.

For a full understanding of my invention reference is made to the accompanying drawings, wherein:

Figure 1 is a transverse vertical section on line 1—1 of Fig. 2, of one form of electrolytic cell for carrying my method into effect; Fig. 2 is a horizontal section of the same on line 2—2 of Fig. 1; Fig. 3 is a horizontal section of a slightly modified form of cell; and Fig. 4 is a partial vertical section on line 4—4 of Fig. 3.

The apparatus shown comprises a covered containing vessel 1, of slate, cement, glass, earthenware or other material capable of withstanding the action of the products of electrolysis, having inlet and outlet pipes 2, 3 for brine, and a chlorin outlet 4. Upon the bottom of the cell I provide any desired number of spaced blocks 5, usually of the same material as the container 1, each block usually having a very slightly concaved upper surface 6 and a central aperture 7. These

blocks support thin layers of mercury 8 which constitute the cathode, this mercury being supplied through pipes 9, 10. In the use of the amalgam for the preparation of hydroxid solutions the supply of mercury 70 will be derived from an oxidizing cell or cells as is well understood. The spaced blocks 5 provide intermediate communicating channels 11 for the reception of the amalgam, these channels being provided with one or 75 more draw-off pipes 12, leading in case caustic soda is to be prepared, to the oxidizing cell above referred to. In order that the quantity of mercury in circuit may not be excessive, I prefer to reduce the area of the 80 channels 11 by blocks 13 suitably disposed therein, these blocks consisting also of refractory material and projecting somewhat above the surface of the mercury. The mercury supporting blocks 5 are preferably 85 of comparatively small sizes, say two to four inches in diameter, and it will be understood that their number may be multiplied as desired to secure increased cell capacity.

In the particular form of cell illustrated 90 the anodes comprise rectangular blocks 14, preferably of Acheson graphite, extending above a row of mercury-supporting blocks 5 and projecting somewhat beyond them as indicated, this construction providing an 95 anode surface which is strictly parallel with that of the cathode and of greater area. Current connection is established through graphite lugs 15 extending through the cover of the cell.

To protect the amalgam in the channels 11 from the action of the electrolyte it may be kept in electrical contact with the cathode, as through pipe 12, and may also be covered with an insulating body 16, which may be 105 a heavy non-conductive liquid inert to the products of electrolysis, or which may comprise a non-conductive and inert solid, as quartz sand, floating upon the amalgam.

In Figs. 3, 4, I have shown a slightly modified form of apparatus wherein the mercury-supporting blocks 5 are elongated and provided with elongated inlet apertures or slots 7. The form or configuration of these blocks may be varied as desired. In this construction the channel 11 may be reduced to a mere slot having an area exposed to the electrolyte sufficient only to convey the amalgam, the mercury being at full flow. As shown in Figs. 3, 4, this is accomplished by refractory 110 blocks 13 as in Figs. 1, 2, but it will be obvious that the same result may be secured by disposing the blocks 5 in suitable proximity to the walls of the cell and to each other.

In the operation of the apparatus shown 125 the flow of mercury through the cell may be continuous or intermittent. If intermittent, a large volume of mercury may be allowed to flow for a brief interval and thus the amalgam cleared from the face of the cup more 130

rapidly and more completely. In either case, the direction of flow is from the center toward the edge at all points and the distance which the mercury has to flow is comparatively very short. The flow of the mercury from the bottom toward the surface from the central orifice of the cup, tends to raise the center above the level of the edges. The amalgam is thus forced from the center toward the edge, at all points. As the amalgam crust reaches the edge it has been observed that the portions of the crust back from the edge are very rapidly pulled after the portions which are in the process of going over the edge, in fact at a velocity much greater than that of the flow of the main bulk of the mercury at the same point. This may be partially due to the fact that liquids flow more rapidly at the surface than at the bottom or sides. It may also be partially due to the cohesion between the particles of amalgam, which pulls on the rear particles in much the same way that one car might pull a train off the end of a trestle. A third influence may be the reduction of the surface tension of the mercury due to the presence of foreign particles on its surface. It is beyond the reach of experimental evidence to prove whether one or all of these causes act, or in what relative degree they act, but the ultimate effect is as described and the amalgam is very rapidly removed from the face of the mercury.

The following advantages of the above-described method may be noted:

1. The amalgam flows but a short distance in contact with the electrolyte, and the capacity of a single cell may be increased as desired without increasing the path of any given portion of the amalgam within the cell. This results in increased efficiency owing to the reduced loss of metal by re-solution in the electrolyte.
2. The time of contact of the mercury with the electrolyte is further reduced, and local action is avoided, by the absence of any solid body or retarding surface in contact with the amalgam while the latter is within the field of electrolysis.
3. A comparatively high cathode current density may be employed, securing thereby increased cathode efficiency and increased

cell capacity; this high cathode current density is rendered possible by the provision of active anode surfaces exceeding the active 55 cathode surfaces in area, and by the reduction in the path of flow of the amalgam and the duration of contact between the amalgam and the electrolyte.

4. The parallelism of the electrodes diminishes local action by avoiding variations in the richness of the amalgam at various points in contact with the electrolyte.

I claim:

1. The method of producing amalgams and alloys which consists in passing an electric current to a plurality of independent bodies of fluid metal beneath a common electrolyte, and supplying the fluid metal to each of said bodies. 70

2. The method of producing amalgams and alloys which consists in passing an electric current to a plurality of independent bodies of fluid metal beneath a common electrolyte, and establishing a substantially 75 radial flow of the fluid metal in each of said bodies.

3. The method of producing amalgams and alloys which consists in passing an electric current to a plurality of independent 80 bodies of fluid metal beneath a common electrolyte, and intermittently supplying the fluid metal to each of said bodies.

4. The method of producing amalgams and alloys which consists in passing an electric current from an anode to a fluid metal cathode, the anode being parallel to the cathode and having a greater active area, and removing the amalgam or alloy by a substantially radial flow without contact with 90 any retarding surface. 85

5. The method of producing amalgams and alloys which consists in passing an electric current from an anode to a fluid metal cathode, and removing the amalgam or alloy 95 by a substantially radial flow out of contact with any retarding surface.

In testimony whereof, I affix my signature in presence of two witnesses.
